UNITED STATES PATENT OFFICE

ABRAHAM ROSENFIELD, OF NEW YORK, N. Y.

BRUSHING MACHINE

Application filed September 15, 1928. Serial No. 306,273.

This invention relates to brushing machines, and more particularly to machines for brushing the fur of garments.

The objects of the invention are to provide a machine by which the fur of made up garments can be properly treated to renew its appearance and improve its character; to enable fur in made-up garments to be readily, properly and thoroughly brushed; to obtain the advantage of machine brushing of fur when in made-up garments; to apply proper pressure and reach all parts of the garments; to apply heat while the fur is being brushed; to electrify the fur; to secure simplicity of construction and operation, and to obtain other advantages and results as may be brought out in the following description.

Referring to the accompanying drawing, in which like numerals of reference indicate similar parts throughout the several views;

Figure 1 is an end view, partly broken away, of a machine embodying my invention, and

Figure 2 is a side elevation of the same.

In the specific embodiment of the invention illustrated in said drawing, the reference numeral 1 indicates a suitable housing or pedestal for supporting the various parts of my improved machine, the housing including a foot 2, an upright portion 3 and a cross-head 4. Under the cross-head I rotatably mount a brush 5 to turn preferably on a horizontal axis. One end of the brush is shown carried in a suitable bearing in a depending flange 6 at the outer end of the cross-head, and the other end of the brush is carried in a bearing in the upright portion 3 of the housing, the axle of the brush being shown as projecting through this latter bearing and has a pulley 7 secured thereon. A suitable motor 8, with pulley 9, is connected by belt 10 to drive the brush continuously and in the proper direction. As shown, the motor is mounted on a shelf 11 on the upright 3, but the exact arrangement and positioning of these parts may be changed as found desirable in manufacture.

Pivoted, as at 12 to the upright, to swing toward and away from the brush in a plane of the axis of the brush, is a narrow table 13.

Said table 13 preferably has a length from its pivot to its free end substantially equal to the length of the brush, and also is preferably positioned beneath the brush in such proximity thereto as to be substantially in contact therewith when the brush and table are parallel. At the pivoted end of the table, I provide an arm 14 which extends beyond the point of pivoting so that the table and arm together form a first-class lever. A tension spring 15 connects the arm 14 with the cross-head, pulling the arm upward and thereby tending to swing the table normally downward away from the brush. The arm is also connected by a depending link 16 to a foot treadle 17 pressure on which will lower the arm against the spring pressure and thereby swing the table toward the brush.

Adjacent the brush, and preferably parallel to it and to the table, when swung toward the brush, is a heating and electrifying roller 18. This roller is also shown as having its bearings in the flange 6 and upright 3 and is actuated by peripheral engagement of the brush and garment therewith. Engagement of the brush with the roller will act to rotate the roller opposite to the direction of rotation of the brush, but the garment is fed through in the direction of movement of the brush at its periphery next to the table, and as viewed in Figure 1 the rotation of the brush is preferably in a clockwise direction with the garment being fed through so it engages the heating roller first. Since that roller is rotating in a counter-clockwise direction it will obtain a rubbing and ironing action upon the fur, and the rubbing action is sufficient to set up a static electric charge in the fur and thus have a tendency to cause the fur to fluff or stand on end. This has a very beneficial effect in aiding the roller to dry and straighten the fur and in enabling the brush to cleanse the fur from foreign matter and lay the fur straight. The roller is electrically heated, an electric cord 19 for that purpose connected to a suitable source of power being shown attached thereto. Since the roller 18 is electrically heated I utilize a material which will transmit the heat without injury to the roller and at the same time which will co-

operate with the garment and brush to obtain an electrification of the fur. It is to be understood, that as the table is pressed toward the brush, with the garment carried upon the table, the fur of the garment is brought into contact both with the brush and with the roller. By this arrangement, the fur is not only brushed, but is also smoothed or ironed, dried and electrified. The table is long enough to accommodate the necessary width of garments, and is shown sufficiently narrow to accommodate cuffs and sleeves when slipped onto the end thereof.

Obviously detail changes and modifications may be made in the construction and use of my improved machine, and I do not wish to be understood as limiting myself to the exact construction or arrangement of parts shown or described, except as set forth in the following claims when construed in the light of the prior art.

Having thus described my invention, I claim:—

1. A machine of the character described comprising a brush rotating on an axis, a table pivoted at one end adjacent one end of the brush to swing toward and away from the said brush in a plane of the axis of the brush, and means for swinging the table toward the brush and applying pressure thereto.
2. A machine of the character described comprising an elongated brush rotating on a substantially horizontal axis, an elongated table pivoted at one end adjacent one end of the brush to swing into substantially parallel relation thereto and having a free end for receiving garments for insertion between the table and brush, and means for swinging the table toward the brush and applying pressure thereto.
3. A machine of the character described, comprising a brush rotating on an axis, a table normally at an angle to the said axis and pivoted so as to swing from said normal angular relationship to a position parallel to said axis, and means for swinging the table toward the brush and applying pressure thereto.
4. A machine of the character described comprising a brush, a table adjacent the brush for receiving a fur garment to be brushed, and a heating roller in substantial contact with the periphery of said brush and with the said table so that the garment may be simultaneously engaged with the brush and heating roller at closely adjacent lines of contact.

ABRAHAM ROSENFELD.
